PROCESS OF TYPOGRAPHIC RELIEFING

Edward M. Hensley, Chicago, Ill.

Application June 23, 1934, Serial No. 732,084

4 Claims. (Cl. 41—25.5)

This invention relates to a process of mechanical relieving previous to typographic printing and particularly to a process of obtaining an overlay for printing half-tones.

5 A principal object of the invention is the provision of a new and improved process for fixing the granular overlay material so as to prevent the same from crumbling or becoming otherwise displaced in use.

10 Another object of the invention is the provision of a process which includes the steps of soaking a relatively thin sheet of tissue or the like in a fixative oil and applying it over a granular overlay material, the thin tissue conforming to the contour and relief of the overlay, and a certain amount of the oil carried thereby being absorbed by the overlay material itself so as to bind the particles thereof together.

15 A further object of the invention is the provision of a process of the character described in which a relatively thin sheet of tissue or the like is sprayed with a fixative oil and superposed on the overlay material, the oil not only rendering the tissue pliable so that it will closely follow the contour or relief of the overlay but also a certain amount of the oil soaking through the tissue and combining with the overlay material so as to fix the same. This spraying operation also exerts a gentle but uniform pressure upon the surface of the tissue such as will insure that it closely conform to the contour and configuration of the underlying overlay material.

20 A further object of the invention is the provision of a process of the character described, in which the powdered materials may be sprayed with a fixative oil and a thin sheet of tissue placed thereon.

25 Numerous other objects and advantages of the invention will be apparent as it is better understood from the following description, which, taken in conjunction with the accompanying drawing, discloses a preferred embodiment thereof.

30 In the drawing, the single figure is a highly magnified vertical sectional view of an overlay prepared in accordance with the instant process.

35 To prepare for printing off it is usual to place on the surface of the cylinder which is to receive the sheet of paper to be printed through pressure against an ink form, a number of reliefs which force the paper to project to a greater extent in such places where a very black print is desired. Such reliefs raise the paper more or less according to the greater or lesser effect desired at a given point. One method of produc-

ing this effect is by pasting bits of paper on a sheet previously printed from the form so as to obtain graduated reliefs in different points according to the effects desired. This is a tedious and lengthy operation and requires the utmost skill and ability.

40 Another well known process is to sprinkle a resinous granular powder over an impression upon a relatively thin foundation sheet obtained from the inked form, which powder adheres more densely and to a greater depth where the ink impression has the greater area.

The present invention is an improvement over this last mentioned process and includes the following steps: After the printing form containing 45 half-tone plates is arranged in position and all plates leveled and made type-high, the form is carefully and thoroughly inked with a special overlay ink. About twice as much ink is used as would be used for regular printing. After allowing the ink to stand on the form for from two to four minutes, a printing impression is made on a special overlay parchment indicated by reference numeral 11 in the drawing, wherein the deposits of ink forming this impression are represented at 50 12. This parchment 11 is preferably relatively thin, transparent, and non-absorbent. Colored overlay which is preferably of a resinous granular matter in grains of convenient size and free of dust, is then carefully spread over the impression thus obtained on the parchment to a thickness of substantially one-fourth inch. The sheet 55 11 is then tilted to allow the excess granular material to slide off into a container for future use, the remainder of the granular material adhering to the inked impression 12 is indicated at 13.

60 Following this, a relatively thin layer of white inert powder, such as flour or the like, is applied over the colored overlay material, and is distributed evenly with a relatively fine brush, care being taken not to scratch or dislodge any of the underlying colored overlay material. The excess white powder is then shaken off and discarded leaving a thin layer 14 on the deposited granular material 13.

65 Following these steps, a sheet of overlay tissue 15 is thoroughly soaked with an overlay fixative oil, such as a mixture of toluol oil, castor oil, and lubricating oil in the approximate ratio of 7 to 3 to 1, respectively, and any surplus oil carefully 70 wiped off. Care must be taken so that the proper amount of fixative oil is spread on the sheet, as an insufficient amount will permit the powdered or granular overlay to crumble and an excess quantity will tend to soften the same.

45

50

55

55

The oil saturated tissue is placed over the overlay material 13, 14—the oil combines with the white powder, making it sticky or paste-like. The overlay is then secured in position under 5 three or four sheets of packing and the tympan and the overlay is ready for a printing operation.

If desired, the tissue 15 may first be positioned over the overlay material 13, 14 and subsequently sprayed with the fixative oil, or the powdered 10 material may be sprayed with the fixative oil and the tissue placed thereon. In either case a certain amount of the fixative oil is absorbed by the underlying granular overlay material so as to bind the particles thereof together and prevent 15 subsequent crumbling.

Moreover, the relatively thin tissue 15 is rendered so soft and pliable that it closely and accurately conforms or clings to the irregularities in the contour and configuration of the overlay 20 material, not only by coherence but also under the action of the spray, when employed. In either event the overlay presents a continuous 25 surface of a relatively permanent nature, the tissue 15 forming a film or skin over the entire overlay. This film or skin not only materially reinforces the granular base of the overlay and increases its life, but it also renders the prints received from the form more clear and distinct.

It is thought that the invention and many of 30 its attendant advantages will be understood from the foregoing description and it will be apparent that various changes may be made in the steps and their order of accomplishment of the process described without departing from the spirit and 35 scope of the invention or sacrificing all of its material advantages, the process hereinbefore described being merely a preferred embodiment thereof.

I claim:

40 1. A process of typographic relieving, which consists in obtaining an impression from an inked form upon a foundation sheet, dusting the

printed surface of the sheet with a resinous powder so as to cause the ink to fix said powder throughout the impression proportionately to the density of the ink thereon, saturating a sheet of tissue with an overlay fixative oil, and securing 5 the soaked sheet in position over said powder.

2. A process of typographic relieving, which consists in obtaining an impression from an inked form upon a foundation sheet, forming a relief overlay by dusting the printed surface of 10 the sheet with a resinous granular substance so as to cause the ink to fix said powder throughout the impression proportionately to the density of the ink thereon, positioning a sheet of tissue over said relief overlay, and subsequently spraying 15 the same with a fixative oil, whereby said sheet is rendered pliable and is pressed into intimate contact with all portions of said overlay material so as to conform to the contour and configuration thereof and whereby a certain 20 amount of the oil absorbed by said sheet is transferred to the granular substance of said overlay so as to bind the particles together.

3. A process of typographic relieving, which consists in providing an overlay of granular material, saturating a sheet of tissue in a fixative oil, and positioning said tissue over said overlay, 25 whereby a certain amount of the oil carried by said tissue will unite with said granular overlay and bind the same together.

4. A process of typographic relieving, which consist in providing an overlay of granular material, positioning a sheet of tissue over said overlay, and spraying said tissue with a fixative oil, whereby said tissue is rendered pliable and 30 forced into intimate contact with all portions of said overlay so as to conform to the relief effect thereof, a certain quantity of the oil carried by said tissue being absorbed by said granular overlay so as to bind the same together.

EDWARD M. HENSLEY.
